UNITED STATES PATENT OFFICE.

SMITH J. HERRICK, OF SANTA CRUZ, CALIFORNIA.

VAPORIZER.

1,359,373.

Specification of Letters Patent. Patented Nov. 16, 1920.

Application filed December 10, 1919. Serial No. 343,713.

To all whom it may concern:

Be it known that I, SMITH J. HERRICK, a citizen of the United States, residing at Santa Cruz, in the county of Santa Cruz and State of California, have invented certain new and useful Improvements in Vaporizers, of which the following is a specification, reference being had to the accompanying drawings.

10 This invention relates to vaporizers and particularly to a vaporizer for inspiratory purposes and has for its object the provision of a device of this character which prevents improper chemical action of the vaporizing substances.

Another object is the provision of a device of this character including a tube for discharging fumes into the vaporizing container, the tube preventing the fuming liquid from entering the vaporizing container.

25 Another object of the invention is the provision of a device of this character including a coil for the passage of fumes having a trap arranged to prevent passage of the fuming liquid into the vaporizing container.

Another object is the provision of a device of this character in which the fuming liquid trap also serves as a connecting member for the sections of the coil so that the parts of the coil may be easily cleaned.

Another object is the provision of a device of this character having a fuming liquid trap from which the liquid can be readily removed without disengaging the tube from the container.

30 A still further object is the provision of a device of this character having an inspiratory tube including means which prevents the entrance of liquid or air into the container.

With these and other objects in view, the invention consists in the improved construction and arrangement of parts to be hereinafter more particularly described, fully claimed and illustrated in the accompanying drawings, in which:—

Figure 1 is a vertical elevation and sectional view of a vaporizer constructed in accordance with the invention.

Fig. 2 is a top plan view.

Fig. 3 is a detail and sectional view of the fuming liquid trap.

Referring to the drawings, 5 indicates a container adapted to receive a medicated

solution in the lower portion thereof. The top of the container, is provided with a plurality of necks 6, which are closed by means of stoppers 7 and 8. The stopper 7 is provided with an opening 9 which extends from end to end and is adapted to support a receptacle 10 in which fuming liquid such as hydrochloric acid is deposited.

The stopper 8, is provided with a pair of 65 openings 11 and 12, the tube 13 being mounted in the opening 11, and extending through the stopper into the container and terminating adjacent the bottom beneath the level of the solution therein. The upper 70 end portion 14 of the tube 13 is extended in right angular relation to the body of the tube and then downwardly and inwardly to provide a projecting partial coil 15. Another tube 16 is provided and serves as 75 an extension of the tube 13. The end 17 of the tube 16 is disposed in the receptacle 10 in spaced relation thereto, while the remaining end 18 is extended in right angular relation to the body of the tube 16 and then 80 bent into a partial coil 19. The end 18 of the coil 19 and the end 15 of the coil 13 are connected to each other by means of a trap 20. This trap is constructed in the form of a T, the branches of the T connecting the 85 ends of the tubes, while the stem 21 of the T is threaded and provided with a cap 22, the stem serving as a trap to intercept any fuming liquid that might pass through the tube 16, the cap 22 permitting the liquid to 90 be readily removed from the trap without disconnecting the tubes 16 and 13 or removing said tubes from the container.

Disposed in the opening 12 of the stopper 8 is an inspiratory tube 23, which terminates at the bottom of the stopper and has its upper portion inclined and provided with a valve chamber 24, in which a ball valve 25 is freely mounted. Extending from the valve chamber 24 is a tube 26 which forms 100 an extension of the inspiratory tube. The end of the tube is provided with a nozzle 27.

In the operation of the device, the medicated solution is deposited in the container, the solution surrounding the lower end of 105 the tube 13. A fuming liquid such as hydrochloric acid is deposited in the receptacle 10. When the user inhales through the inspiratory tube 13, the suction at the same time causes fumes to rise from the 110 fuming liquid in the receptacle 10 to pass upwardly through the tube 16 around the

coil, down the tube 13 into the medicated solution, where a chemical action takes place to produce vapors which rise to the top of the container and are discharged 5 therefrom with the same suction. During this operation, should the force of inhaling be so great as to cause the fuming liquid to enter the tube 16, the trap 20 will receive the liquid and permit only the fumes there- 10 of to pass through the remainder of the coil and down through the tube 13 into the medicated solution.

From the foregoing, it will be readily seen that this invention provides a novel 15 form of vaporizer which through the provision of the coil in the tubes conveying the fumes, prevents improper chemical action so that vapor of the proper quality and strength is produced in the container. 20 Any liquid that may have collected in the trap 20 can be readily removed therefrom without disengaging the tubes 13 and 16 from the container by simply removing the cap 22 from the trap.

25 The invention having been set forth, what is claimed as new and useful is:—
1. A vaporizer of the character described comprising a container, means for closing the open end of said container, a tube in- 30 cluding a coil supported by said means, said tube having a trap, an outlet for said trap, one end of said coil extending into the container and terminating adjacent the bottom thereof, the other end extending into 35 a fuming liquid receptacle carried by the container.

2. A vaporizer of the character described comprising a container, means for closing the open end of said container, a tube in- 40 cluding a coil supported by said means, said tube having a trap, an outlet for said trap, one end of said coil extending into the container and terminating adjacent the bottom thereof, the other end extending into 45 a fuming liquid receptacle carried by the container, said coil separating the fuming liquid from the fumes thereof.

3. A vaporizer of the character described comprising a container, means for closing the open end of said container, a tube in- 50 cluding a coil supported by said means, said tube having a trap, an outlet for said trap,

one end of said coil extending into the container and terminating adjacent the bottom thereof, the other end extending into 55 a fuming liquid receptacle carried by the container, said trap co-operating with the coil to prevent the passage of fuming liquid through the tube disposed in the container.

4. The combination with a container hav- 60 ing openings in its top, a stopper for each opening, a liquid receptacle carried by one of said stoppers, of a tube coiled adjacent its intermediate portion to provide a fume and liquid separator, the long end portion 65 of said tube being mounted in another of said stoppers and extending through the same into the container, the short end portion extending in the direction of the long end portion and in parallel relation thereto, 70 into said receptacle, a trap carried by said coil and vapor outlet means carried by said second mentioned stopper.

5. The combination with a container hav- 75 ing openings in its top portion, a stopper for each opening, a fuming liquid recep- 80 tacle carried by one of said stoppers, of a tube supported by another of said stoppers, one end portion of said tube extending through the stopper into the container, the other end portion being partially coiled, a 85 second tube having one end disposed in said receptacle in spaced relation to the wall thereof, the other end of said second men- 90 tioned tube being partially coiled, a trap connecting the coiled end portions of the tubes to each other, said trap having an outlet and means for closing said outlet.

6. A vaporizer of the character described comprising a container, stoppers for said 90 container, a fuming liquid receptacle sup- 95 ported by one of said stoppers, a sectional coiled tube having one end disposed in the receptacle, the other end extending through another of said stoppers and terminating adjacent the lower portion of the container, a fuming liquid trap in said coil, said trap having an outlet, and a tube extending through the last mentioned stopper, said tube including a valve, and a nozzle on the 100 other end of said tube.

In testimony whereof I hereunto affix my signature.

SMITH J. HERRICK.
